UNITED STATES PATENT OFFICE.

VINCENT GROOM, OF. LONDON, ENGLAND.

FURNACE FOR THE PREPARATION OF ARTIFICIAL FUEL.

1,187,305.

Specification of Letters Patent. Patented June 13, 1916.

Application filed April 24, 1916. Serial No. 93,301.

To all whom it may concern:

Be it known that I, VINCENT GROOM, a subject of the King of Great Britain, residing at 392 Kennington road, London, S. E., England, have invented new and useful Improvements in and Relating to Furnaces for the Preparation of Artificial Fuel or the like, of which the following is a specification.

10 In the manufacture of artificial fuel, whatever the process employed may be, great difficulties are always encountered in the coking of the mixed materials when formed into shape as briquettes or the like. In coking furnaces employed for coking the fuel mixture, it has been proved in practice that the charge of fuel mixture subjected to the coking operation is not heated in a uniform manner, and consequently there are, between 15 different briquets or ovoids (egg-shaped fuel) large differences as regards the degree of elimination of the volatile constituents of the fuel and as regards the power of resistance to a crushing action.

20 The present invention has for its object a heating apparatus or furnace which allows of obviating these disadvantages.

On the accompanying drawing is shown by way of example, a furnace provided according to the present invention.

Figure 1 is a horizontal section of the oven which is shown in vertical section in Fig. 2, this vertical section being taken partly along the line A—B and partly along 35 the line C—D of Fig. 1. Fig. 3 is a view of the receptacle in which the material to be heated is placed.

As will be seen from Figs. 1 and 2, the furnace consists of a chamber 12 inclosing a 40 number of heating units 13. Each heating unit 13 is independent of the rest and consists of a series of heating chambers 2 provided above combustion chambers 1, the heating chambers communicating by means 45 of apertures 10 in their inner walls 9 with a central flue 3. This flue 3 communicates by means of apertures 14 with the combustion chambers 1, so that the volatile matters given off from the substances treated are utilized 50 to maintain the fires in the combustion chambers.

The heating units are surrounded by passages 4 and the combustion chambers 1 communicate with these passages by means of 55 apertures 11. Thus the products of combustion pass out from the combustion chambers

into the passages 4 and circulate over and around the heating units before their exit to the chimney of the furnace in the direction of the arrow 5. A central flue 15 between the flues 3 affords a passage for the hot gases of combustion from top to bottom of the chamber 12 between the series of heating chambers 2.

The natural draft of the chimney drawing 65 the excess of volatile substances through the flues 3 and the products of combustion through the passages 4 may be increased by the use of a fan if desired or thought necessary.

70 In each of the heating chambers 2 is enclosed a receptacle 6, the sides and bottoms of which are perforated by apertures 7 (see Fig. 3), which apertures allow of a regular distribution of the heat through the mass of 75 ovoids to be coked.

The sides and bottoms of the receptacles 6 may instead of being plain, be fluted so as to give a still more uniform circulation of air over them, and avoid the use of supports or pedestals which are necessary when employing receptacles with plain or flat bottoms.

75 The back and front walls of the furnace are formed by a metallic casing 8 in which 80 doors are provided, allowing of access to the heating-chambers 2. This arrangement allows of coking the fuel very quickly and consequently of reducing to a considerable extent the amount and duration of heating 85 necessary to drive off the excess of volatile constituents.

I claim:

1. A furnace for coking or carbonizing combustible substances, comprising in combination a plurality of independent heating units, each separated from the inner walls of the furnace and from its neighboring unit by passages for conveying the products of combustion from said units to a single main 100 exit flue, and each unit consisting of a combustion chamber or chambers, a series of heating chambers heated by the latter, a flue common to said series providing communication between the heating chambers and the 105 combustion chamber or chambers, and means of communication between said heating units and the passages aforesaid, together with incombustible receptacles for holding the material to be treated.

110 2. A coking furnace including a main chamber, a plurality of heating units ar-

ranged in spaced parallel relation with each other, and spaced from the inner walls of the main chamber to provide flues, superposed heating chambers in each of the heating units, means for providing communication between the heating units, and a fuel receptacle in each heating chamber.

3. A coking furnace including a main chamber, a plurality of heating units arranged in the main chamber, superposed heating chambers in each of the heating

units, means for providing communication between the heating units, a heating chamber formed in each heating unit, and a receptacle in each heating chamber, said receptacles having their side walls and bottom perforated. ¹⁵
